UNITED STATES PATENT OFFICE.

FREDERICK R. WATERS, OF OURAY, COLORADO.

MINING-HAMMER.

SPECIFICATION forming part of Letters Patent No. 624,883, dated May 9, 1899.

Application filed February 23, 1899. Serial No. 706,548. (No model.)

To all whom it may concern:

Be it known that I, FREDERICK R. WATERS, of Ouray, in the county of Ouray and State of Colorado, have invented a new and Improved Mining-Hammer, of which the following is a specification.

In drilling in mines the drill often sticks or wedges in the hole and its extraction involves more or less time and labor and is occasionally somewhat difficult.

It is the object of my invention to so construct the head of a miner's hammer used for driving such drill as to enable it to be conveniently used for effecting removal of the drill with ease and despatch. To this end I provide the hammer-head with a central transverse groove extending across its outer side and adapted to fit upon or receive the body of the drill. The construction and manner of use of such hammer are as hereinafter described, and shown in the accompanying drawings, in which—

Figure 1 is a perspective view showing my improved hammer as in use, and Fig. 2 is a perspective view of the same.

The hammer-head A is provided with a deep transverse groove B, the same extending across its outer side and being formed in the body of the head, so that the latter has no projection at that point. The groove is semicircular in shape and arranged equidistantly from the ends of the head A and directly opposite the hole or socket in which the handle C is secured. It is of such form, depth, and diameter as required to adapt it to receive the body of a drill. The form and size of the ends of the head A are similar.

When a drill X becomes fast in the drill-hole, the miner applies the hammer-head A

thereto, as shown in Fig. 1, so that the body 40 of the drill lies partly in the groove B, which it traverses, the handle C being thus necessarily at right angles to the drill. Then by sliding the head A backward and forward on the drill a blow or series of blows may be delivered against the enlarged head of the drill, so that it is quickly extracted with little difficulty—that is to say, as the hammer-head A is moved outward it strikes the flange of the drill-head, and thus applies to the drill an extractive blow of greater or less force. It will be noted that this operation is facilitated by the central arrangement of the groove B in the hammer-head and by its formation in the body of the latter, since the torsion, leverage, 45 and jar upon the handle C are thus reduced to a minimum.

The body of the hammer will be slightly increased in certain proportions in order to compensate for the weight of the material removed 50 by the groove B, and the central portion of the hammer will have increased strength around the eye or handle-socket.

What I claim is—

1. A miner's hammer having its head provided with a transverse groove extending across its outer side, the same being central or equidistant from its ends, which are similar in form and size, as shown and described. 65
2. A hammer-head for miners' use, having a transverse groove in its outer side, the same being sunk in the body of the head, whereby the latter is adapted for use upon a drill, as and for the purpose specified. 70

FREDERICK R. WATERS.
